UNITED STATES PATENT OFFICE

2,259,457

POWDERED METAL AND ALLOYS

William Andrew Croll, Norristown, Pa.

No Drawing. Application January 12, 1938,
Serial No. 184,703

8 Claims. (Cl. 252—303)

My invention relates to finely divided metals, alloys, metallic compounds and various other materials which it is desired to produce in powdered form, and the method of forming the same. More specifically my invention relates to converting to powdered form stainless steel, tungsten, molybdenum, tantalum, titanium and their carbides; the double carbides of tungsten and titanium; the metals nickel, cobalt, copper, lead, zinc, graphite, iron oxide, Bakelite (phenol-formaldehyde condensation product), tin, Prussian blue, silver and other precious metals, and various metallic and non-metallic materials which are crushable and which it is desired to obtain in powdered form.

I can convert these materials to such finely divided form that they can form substantially permanent suspensions in liquids such as water and are susceptible to Brownian movement. Metal powders have long been made since they have a great commercial value in certain processes. Thus, metallic objects can be formed from metal powders instead of from cast molten metals and definite advantages such as purity of product, exactness of size, simplicity of manufacture, predetermined grain structure, etc., are obtained. The advantages of manufacture from powdered materials are well known, but many disadvantages have hitherto been attendant upon their use. First, it has been impossible to obtain alloys in powdered form. This is because customarily powders were made by depositing the metal as by chemical precipitation or by electric deposition followed by grinding the so formed metal to the desired powder size. Since alloys cannot be chemically precipitated or electrolytically deposited, they cannot be formed in powders.

According to my process, I can form powdered materials of a finer particle size than any hitherto produced. In addition, I can powder alloys and certain other materials which it has been found impossible to powder heretofore according to the known processes. Because of the particle size which I produce, I secure superior results in the formation of molded metal objects. The flaws that have hitherto been incidental to the casting processes are completely eliminated by the use of my powders.

I can also combine certain metals such as copper and tungsten which cannot be produced in the ordinary alloy forms. Because I obtain these metals in such fine particle size, I can combine them in desired proportions to obtain finished products of predetermined qualities. Thus, a new field of combinations of metals for desired purposes, which metals cannot be alloyed by the ordinary means, is opened by my process.

Further, my process affords to certain easily oxidizable materials, a surface protection that

prevents oxidation and makes available such materials in this desirable finely powdered form. An outstanding example of such material that hitherto has been found impossible to powder because of its oxidizing tendencies is Swedish iron. Powdered Swedish iron can be produced according to my process and shows no tendencies to oxidize after being reduced to this finely divided form.

10 Further, because of the fine particle size which I can obtain with my process, I can form suspensions of the ground materials in water which are substantially permanent in that for practical commercial purposes they will not settle out. 15 My process involves crushing material to be ground as for example in a ball mill in such a way and under such conditions so that when separation of one particle from the mass is effected by the crushing means, certain substances present in the mixture which will not chemically react with the crushed material, surround the particle and carry it away from the mass so that it is exposed for further crushing without impairing the crushing effect on the larger mass from which it has been separated. Thus, it is the purpose of my invention to continuously form a suspension of the small particles of the material to be ground in the ball mill so as to provide the most opportunity for the crushing effect 20 of the balls of the ball mill.

25 Specifically, for example, in the crushing of the metal, I add to the customary metal and water mixture that is placed in the ball mill, saponin and an auxiliary material such as salacin. 30 The saponin acts to separate the crushed particles one from the other and to create more or less of an emulsion of the materials in the water. The salacin prevents the saponin from forming a froth and has a certain separating action in itself.

35 In lieu of the saponin, I may use any saponin type of material. In lieu of the salacin, I may use any material that can be converted to a dextrose, such as salacin, papain, lactose or sugar, 40 and also materials of the tannic acid and gallo-tannic acid groups. It is extremely important that quantities of the materials selected be such that no froth or foam be formed in the ball mill.

45 I have found that a great number of the materials which are ground to fine particle size according to my invention when thrown into water move about in the water in conformity with what is known as the Brownian movement. That is, the particles continuously move toward and away from each other in unceasing movement. This apparently is due to the fact that the particles 50 are in such fine finely divided form.

55 The object of my invention is to produce finely divided alloys and metals such as stainless

steel, tungsten, molybdenum, tantalum, titanium and their carbides; the double carbides of tungsten and titanium and the metals nickel, cobalt, copper, lead, zinc, graphite, silver and other precious metals, iron oxide, Bakelite, tin, Prussian blue and various metallic and non-metallic materials.

A further object of my invention is to convert crushable materials to finely powdered form.

A further object of my invention is to produce such alloys, metals, metallic and non-metallic materials and pigments in such a state of subdivision that they are susceptible of Brownian movement.

A further object of my invention is to provide a novel process for the production of extremely fine metal powders.

A further object of my invention is to produce these extremely fine powers by means of a ball milling operation substantially without using a foam.

It is a further object of my invention to provide a mixture of crushable material, water and saponin for the ball mill grinding.

It is a further object of my invention to provide a mixture of crushable material, water, saponin and a material capable of being converted to a dextrose for the ball mill grinding.

According to my preferred method, I employ a ball mill comprising a cylinder with a number of grinding pebbles, balls or rods contained therein. The cylinder is adapted to be rotated about a horizontal axis so as to cause the pebbles, balls or rods contained therein to be tumbled upon themselves whereby they thoroughly crush and grind any material distributed therethrough. In this ball mill machine, I place a mix comprising,

1			
Stainless steel	oz.	4	40
Quillaja extract	cc.	30	
Ammonium hydroxide	cc.	15	
Water	cc.	2,000	

The stainless steel is in the form of rather small pieces, such as chips, or any other suitable small form of stainless steel. The quillaja extract is formed from Quillaja saponaria, a wood of which the principal chemical constituents are saponin and calcium oxalate. One ounce of the quillaja wood is digested with one pint of warm water. The wood is left to digest in the warm water for a period of about one hour and then filtered. The filtrate is known as quillaja extract. When this extract is boiled, as shall be described later in this specification, it is converted into saponin $C_{14}H_{22}O_{10}$ and glucose. This saponin is insoluble in water. In place of the quillaja extract, saponin (senegin) $C_{18}H_{30}O_{10}$ may be employed.

The mill with the mix contained therein is turned for about 48 hours to thoroughly grind the stainless steel. This grinding period may obviously be varied depending on the degree of fineness desired. After this grinding period, the mill is opened and the liquid is taken out down to the level of the pebbles. The liquid taken out is replaced by a mixture of about 15 cc. of ammonium hydroxide and sufficient metal to replace that withdrawn in the change and enough water to make up the quantitative difference of the liquid withdrawn. The ball mill is again rotated for a period of about five hours. The R. P. M.'s of the mill range from 35 R. P. M. for a large five ton mill to about 50 R. P. M. for a one gallon mill. At this time all the liquid above

5

the level of the pebbles or balls is again withdrawn. The liquid that has been withdrawn from the ball mill as above indicated is treated to extract the finely divided stainless steel contained therein. The stainless steel in finely divided form can be extracted from the aqueous mix by boiling. This boiling settles the powders out of the mixture. If desired, the liquid can be boiled off entirely. This results in the deposition of the minutely divided stainless steel. Alternatively the stainless steel can be extracted by adding an acid which reacts with the ammoniacal solution to precipitate the finely divided stainless steel. This acid can be a mineral acid such as sulphuric acid or hydrochloric acid. Again, a salt such as sodium chloride or caustic alkalis may be employed. Further, the solid particles may be extracted from the liquid by means of a centrifuge. Each quantity of liquid drawn off from the ball mill as above-indicated yields at least one-quarter ounce of the finely divided stainless steel.

			25			
Iron oxide	oz.	4		In the case of silver, Example 6, it is preferable not to use ammonium hydroxide since silver fulminate which is highly explosive may be formed. In this case I may use an ammonium salt. Further, in connection with certain of the metallic compounds, as for example Prussian blue, ammonia should not be added in any form since it would react with the iron causing it to turn brown. Obviously, the ingredients of the respective mixer should be carefully selected to prevent undesirable chemical reactions. A few acids of the tannin group do not produce best results.

Ammonium hydroxide	oz.	1				
Water.						
			50			
Prussian blue	oz.	4		It is to be noted in each of these examples saponin or its equivalent quillaja extract was used. This saponin or saponin type material has the peculiar effect of surrounding and separating the small particles of the material and carrying these particles off into the liquid mix. There the particles are held in the form of a suspension and are positioned in the best possible manner to receive individually the blows of the falling balls of the ball mill. As I have indicated, it is important that the amount of saponin or saponin like material in the mixture be carefully regulated so that no froth is formed since the froth has been found to seriously interfere with the proper operation of my process. As is to be noted from these examples, salicin or papain or tannic acid or

gallotannic acid or sugar or gallic acid or combinations of these are also added and serve a very useful purpose. They aid in the prevention of a froth and they have an auxiliary action with the saponin in acting to separate the particles of material. Although their exact action is not fully understood, I have found it to be a fact that their use in combination with the saponin definitely improves the process. I have also found that I can use this second class of materials without saponin although the results in that case are not as good as when saponin is employed. This shows, however, that these materials have a certain coating and separating action in themselves.

In the powdering of Swedish iron where oxidation is a serious factor these materials which are capable of being converted to dextrose apparently coat the powdered material with a very fine almost microscopic coating that affords protection against oxidation. Ammonium hydroxide is added because of the improved results obtained with it and, I have found that its presence in the mixture causes a vacuum to be created during the grinding process. This vacuum is believed to be of aid in the grinding operation of my invention.

It is my theory that the extremely fine metal powders are formed by process as differentiated from the processes of the prior art for these reasons. Heretofore, in these ball mills as the balls or pebbles pounded upon the metal particles to produce the metal powder the external portion of the metal particles was crushed and powdered and the crushed or powdered portion of the metallic particle tended to cushion the remaining major portion of the metal particles against further crushing by the blows of the balls of the ball mill. Thus, as each particle became partially crushed it became increasingly difficult to effect the subdivision and breaking down of the metal particles of comparatively large size. However, in my method as soon as the external portion of the metal particle is fractured or crushed, it is separated and carried away by the material which surrounds it if it is sufficiently small. The rapid and uniform action of the added materials, above indicated in the different mixes, in removing those small particles of finely divided metal which would tend to protect the metal particle against subdivision is a primary feature of my invention.

In addition, as these small particles are held in suspension separated one from the other they are continually being struck by the tumbling balls to further reduce them in size. Thus, instead of a group of small particles being pressed in a mass or pressed while in contact with large particles as in the process of the prior art, according to my novel process each particle and section of a particle is separated and held off one from the other while being further reduced in size by the tumbling balls.

I have reiterated throughout this specification that my finely divided powders are of a size far below that hitherto known. As a test for the fineness of my particles, I form a mixture of from one part of finely divided metal and two parts of water. I have found that when such a mixture is made with my finely divided metal powders it will pass through an average filter paper.

Although I have set forth a specific process for forming my finely divided metal powders, it is to be understood that alternative methods may be used. Thus, in place of the ball or pebble mill

I may employ a suitable grinding or crushing means.

A surprising result of my process has been the production of pure iron such as Swedish iron in a fine powder state without iron oxidizing. It has been found that if iron be powdered according to the prior processes, it oxidizes in twenty-four hours. I have reduced iron to the fine particle size indicated by my process and subjected it to an oxidizing atmosphere for three weeks without such objectionable oxidation taking place. These same phenomena have been observed with other easily-oxidizable materials.

A further important feature of my process is production of powdered hard carbides without injury to the grinding mill. Previous attempts to powder hard carbides have resulted in serious cutting of the mill. Further, powdered hard carbides have been produced in one-tenth the time found necessary in previous processes.

Peculiarly enough, I have found that hard carbides can be easily ground to a fine particle size according to the process I have set forth. This is in marked contrast to the prior grinding processes which have found such carbides extremely difficult if not impossible to powder. In the same way I have found many other materials that are particularly hard in structure easy to reduce to fine particle size. Apparently when in my process the small pieces are held in a suspension apart from the rest of the mixture, they are easily fractured by the blows of the grinding mill.

I claim:

1. The process of pulverizing metals which comprises crushing the material; carrying away from the remaining mass of material the particles as they are separated from the mass in a water solution containing a saponin and a material that can be converted into a dextrose leaving the uncrushed mass of material exposed for further crushing; and periodically removing the water solution containing the powdered substance in suspension.

2. The process of pulverizing metals which comprises crushing the material; carrying away from the remaining mass of material the particles as they are separated from the mass in a water solution containing saponin and salacin leaving the uncrushed mass of material exposed for further crushing; and periodically removing the water solution containing the powdered substance in suspension.

3. The process of pulverizing metals which comprises crushing the material; carrying away from the remaining mass of material the particles as they are separated from the mass in a water solution containing saponin leaving the uncrushed mass of material exposed for further crushing; and periodically removing the water solution containing the powdered substance in suspension.

4. The process of pulverizing metals which comprises crushing the material; carrying away from the remaining mass of material the particles as they are separated from the mass in a water solution containing saponin and an auxiliary material leaving the uncrushed mass of material exposed for further crushing; and periodically removing the water solution containing the powdered substance in suspension.

5. The process of pulverizing metal alloys which comprises crushing the material; carrying away from the remaining mass of material the particles as they are separated from the mass in

a water solution containing saponin and a material that can be converted into a dextrose leaving the uncrushed mass of material exposed for further crushing; and periodically removing the water solution containing the powdered substance in suspension.

6. The process of pulverizing metal alloys which comprises crushing the material; carrying away from the remaining mass of material the particles as they are separated from the mass in a water solution containing saponin and a material that can be converted into a dextrose leaving the uncrushed mass of material exposed for further crushing; periodically removing part of the water solution containing the powdered substance in suspension; replacing the removed portion of the water solution with an equal amount of fresh water solution and material to be pulverized together with ammonium hydroxide; and removing the powdered metal from the water solution.

7. The process of pulverizing metal alloys which comprises crushing the material; carrying away from the remaining mass of material the particles as they are separated from the mass in a water solution containing saponin and a mate-

rial that can be converted into a dextrose leaving the uncrushed mass of material exposed for further crushing; periodically removing part of the water solution containing the powdered substance in suspension; replacing the removed portion of the water solution with an equal amount of fresh water solution and material to be pulverized together with ammonium hydroxide; and removing the powdered metal from the liquid by boiling the water solution.

8. The process of pulverizing metal alloys which comprises crushing the material; carrying away from the remaining mass of material the particles as they are separated from the mass in a water solution containing saponin and a material that can be converted into a dextrose leaving the uncrushed mass of material exposed for further crushing; periodically removing part of the water solution containing the powdered substance in suspension; replacing the removed portion of the water solution with an equal amount of fresh water solution and material to be pulverized together with ammonium hydroxide; and removing the powdered metal from the liquid by adding an acid to the water solution.

WILLIAM ANDREW CROLL.
